UNITED STATES PATENT OFFICE.

GEORGE W. TUCKER, OF POTTSVILLE, PENNSYLVANIA.

INSULATED RAIL-JOINT FOR ELECTRIC SIGNAL SYSTEMS.

1,373,387.

Specification of Letters Patent. Patented Mar. 29, 1921.

Application filed January 5, 1921. Serial No. 435,189.

To all whom it may concern:

Be it known that I, GEORGE W. TUCKER, a citizen of the United States, residing at Pottsville, in the county of Schuylkill and State of Pennsylvania, have invented certain new and useful Improvements in Insulated Rail-Joints for Electric Signal Systems, of which the following is a specification, reference being had to the accompanying drawings.

In some insulated rail joints heretofore used, the adjoining ends are supported by metal chairs or bridging-plates, extending across the joint and provided at one or both sides of the rail with upright flanges, there being interposed between the flanges, and the webs of the rail wood packings or fillings, and through which transverse fastening bolts are passed. This construction requires insulating material to be interposed, not only between the ends of the rails, but also between their bases and the metallic chairs, and between the transverse bolts and the flanges of the chairs. In such construction the wood fillings and the insulation in time become crushed, while the bottom insulation becomes battered or shifts out of place, rendering the joint expensive to maintain, and unsafe and unreliable in use.

In the present invention it is an object to provide an insulation, wherein a bottom flange or plate and an end post are combined, there being two between the adjacent or adjoining ends, eliminating a separate insulating base and a separate end post, thereby obviating the danger of a shifting movement of the insulating material, particularly its base, also increasing the life of the insulating material, lessening the expense of maintenance, and making the insulated joint more reliable and durable.

It is a further purpose to increase the life of the insulating material, by interposing a sheet metal angle plate preferably of steel between the bottom and the end of the rail and the insulating base and end post.

It is still further an object to provide a joint insulation between two rails, especially in connection with an electric signal system, comprising a pair or two separate combined base plates and end posts, eliminating the wear which would ordinarily occur, should a continuous insulating base material be used.

It is obvious that this type of insulation

can be applied to all types of insulated joints, now in use on railways, especially in connection with railways where automatic signaling systems are employed, and where a chair or base plate is used under the rail, causing the continuation of the rails.

An advantage of the present invention is to provide an insulating base and end post, which will not crawl out of or from the joint under heavy traffic, or will not shift, for the post and plate are formed in one piece, and where they are connected, the rails are prevented from cutting through the base.

A further advantage is to provide a form of joint insulation, which may be cheaply manufactured and sold at a reasonable profit, and also to provide an insulating device, wherein there is rendered a saving of substantially one half of the insulating material heretofore used.

While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features and combination of parts, as will be herein-after set forth, shown in the drawings and claimed.

In the drawings:—

Figure 1 is a view in side elevation of the adjacent or adjoining end portions of two rails, showing the improved insulating joint between the rails.

Fig. 2 is a detail perspective view of one of the insulating members, showing the angle insert plate as engaging therewith.

Fig. 3 is a detail perspective view of the angle insert plate.

Fig. 4 is a sectional view on line 4—4 of Fig. 1, showing how the rails are connected.

Referring more especially to the drawings, 1 designates each of the insulators as a whole of the rail joint, and said insulator comprises a base 2, which engages between the tie and the rail base, and 3 denotes the end post, which engages between the adjoining or adjacent ends of the rails. The insulator may be constructed of any suitable insulating material, such as the usual

fiber employed for this purpose, and it will be noted that the end post is formed at right angles to the base. The end post 3 is of a shape corresponding to the shape of 5 the rail in cross-section, so that the edges of the post are flush with the surface of the rail.

When insulating rail joints, for the purpose of dividing a track into blocks, for 10 block signal systems, two insulators are employed. The insulators are arranged as shown in the drawing, so that the bases 2 will extend in opposite directions, and upon which the bases of the rails rest. It will be 15 noted that the posts 3 of the adjacent ends of the bases of the insulators engage each other, and are disposed between the adjoining ends of the rails, thereby insulating one rail upon the other.

20 Engaged with and conforming to the angles of the insulators, at points where the end posts rise upwardly from the bases are reinforcing insert plates 5, which are angular in cross-section, and may be constructed of any suitable metal, preferably steel. The 25 purpose of making the insert plates relatively thin, is to provide means to support the bases of the rails a relatively small distance above the upper surface of the bases 30 of the insulator so as to avoid producing an excessively uneven track.

As a further reason for the insert plate 35 5 with its flanges 6 and 7, particularly the flange 7, is to space the rails a requisite distance by means of the insert plates, so as to give the rails a chance to expand and contract without injury to the upper part of the insulation. In Fig. 1 the flanges 7 are slightly thicker than the flanges 6, to insure 40 the expansion and contraction of the rails.

Furthermore the steel insert plates constitute means, to prevent the corner portions of the rail bases from cutting into and tending to crush or otherwise injure the insulators, particularly at the points where the 45 end posts rise upwardly from the bases. Heretofore insulators were injured considerably, and crushed, or otherwise cut by the ends of the rails, particularly due to the 50 creeping of the rails as a result of the traffic of the car wheels thereon, and also due to the expansion and contraction of the rails, hence the provision of the steel insert plates to insure protection for the insulators.

55 These insert plates may be held in place in any suitable manner, preferably through the medium of the rail ends resting thereon, in fact due to the frictional contact therewith, or they may be retained in position by any 60 other suitable means (not shown). It is obvious that when these insert plates become worn and are not serviceable for the purpose intended, they may be easily replaced by new ones, and in this way enabling the 65 insulators to be used substantially indefi-

nitely. In other words a construction of this kind renders the insulators very durable, and owing to the simplicity of construction of the insulators and the insert plates, the insulating means may be cheaply 70 manufactured, and sold and installed at a reasonable profit.

In order to connect the adjacent rail sections 8, and at the same time insulate one rail section from the other, and also not in- 75 cumbering or involving complicated construction wooden filler blocks 9 are disposed adjacent the webs of the rail sections between the bases and the under parts of the ball of the rail sections, there being the usual 80 bolts 10 passing through the blocks and the rail sections. A metallic chair or bridging plate is disposed under the bases 2 of the insulators. This metal chair or bridging plate is designed to be supported on the tie (not 85 shown). The longitudinal edges of the metal chair or bridging plate 11 have up- 90 standing flanges 12, and interposed between the flanges 12 and the wooden filler blocks are angle side plates 13. It will be noted 95 that the wooden filler blocks are thicker than the lateral portions of the bases of the rail sections; therefore the filler blocks overhang the side edges of the bases of the rail sections, hence spacing the side angle plates 95 from the bases of the rail sections. These angle side plates are designed for the purpose of strengthening the joint between the rail sections. The bolts 10 pass through the upstanding flanges of the side angle plates 100 and are provided with nuts 14, to hold the parts together. In order to insulate the angle side plates from the rail sections and prevent the transmission of current, the bolts 10 pass through flanged fiber bushings 105 14^a, which are engaged in openings 15 of the upstanding flanges of the side angle plates. Interposed between the flanges of the bushings 14^a and the heads and nuts of the bolts, and surrounding the outer ends of 110 the bushings are washers 16 of any suitable metal preferably steel. The heads and nuts of the bolts engage the washers, and insure a firm or rigid construction. Suitable bolts 17 are disposed upwardly through the metal 115 chair or bridging plate and through the horizontal portions of the side angle plates, and through sheet metal plates 18, and are provided with nuts 19. By means of the bolts 17 the side angle plates and the rail sections are connected securely to the metal chair or bridging plate, which may be fastened to the tie (not shown) in any suitable manner. Each bolt 17 passes through an individual sheet metal plate 18, which 120 has opposite bent portions 20, one co-operating with the nut 19, the other overlying and extending on down the outer portion of an upstanding flange 12. These bent portions 20 act to hold the sheet metal plates 18 in 125 130

place, and prevent the nuts 19 from turning. The plates 18 act as washers between the nuts 19 and the lateral portions of the side angle plates.

5 The invention having been set forth, what is claimed as being useful is:—

1. In an insulated rail joint for signaling systems, a pair of adjoining rail ends, insulators angular in cross-section comprising bases engaged under the rail bases and adjacent end posts corresponding to and engaging between the adjoining rail ends, and a metallic insert angle plate engaging the insulators at the angle portion where the posts 10 rise from the bases, said insert plates constituting means to support the rail bases slightly out of contact with the bases of the insulators, and to space the end rails from the end posts.

15 2. In an insulated rail joint, a pair of adjoining rail ends, insulators engaging between the adjoining ends and having bases engaging under the rail bases, and insert reinforcing means interposed between the

angle of the insulators and the bases of the 25 rails, and between the ends and the upstanding posts of the insulators.

3. As an article of manufacture, a rail joint insulator comprising an elongated base, and an end post rising upwardly from one 30 end of the base, the end post adapted to engage the rail end, while the base engages under the rail base, and a reinforcing insert plate engaging the angle adjacent where the post and the base of the insulator unite. 35

4. In combination with a rail end and a right angle insulator adjacent the rail end, an article of manufacture comprising an insert plate consisting of a base to engage between the base of the rail and the insulator, 40 one end of the base of the insert plate having an upstanding flange engaged between the rail end and the upstanding portion of the insulator.

In testimony whereof I hereunto affix my 45 signature.

GEORGE W. TUCKER.
